UNITED STATES PATENT OFFICE

98,711

DESIGN FOR A BOTTLE

Hyman C. Berkowitz, Boston, Mass., assignor to Ben-Burk, Inc., Boston, Mass., a corporation of Massachusetts

Application December 14, 1935, Serial No. 60,084

Term of patent 14 years

To all whom it may concern:

Be it known that I, Hyman C. Berkowitz, a citizen of the United States of America, residing at Boston, in the county of Suffolk and State of Massachusetts, have invented a new, original, and ornamental Design for a Bottle, of which the following is a specification, reference being had to the accompanying drawings, forming part thereof.

In the drawings,

Fig. 1 is a front view of a bottle showing my new design;

Fig. 2 is a section on line 2—2 of Fig. 1; and

Fig. 3 is a rear view of the bottle shown in Fig. 1, the closure cap being omitted.

I claim:

The ornamental design for a bottle, substantially as shown.

In testimony whereof I affix my signature.

HYMAN C. BERKOWITZ.
